ATTORNEY.

UNITED STATES PATENT OFFICE.

ALBERT E. MOORHEAD, OF SAN FRANCISCO, CALIFORNIA.

PNEUMATIC SWEEPER.

No. 927,668.

Specification of Letters Patent.

Patented July 13, 1909.

Application filed October 28, 1908. Serial No. 459,948.

To all whom it may concern:

Be it known that I, ALBERT E. MOORHEAD, a citizen of the United States, residing at San Francisco, in the county of San Francisco and State of California, have invented new and useful Improvements in Pneumatic Sweepers, of which the following is a specification.

The object of the present invention is to provide a pneumatic sweeper, which shall be simple in construction and convenient and effective in operation.

In the accompanying drawing, Figure 1 is a transverse vertical section of the sweeper on the line 1—1 of Fig. 2; Fig. 2 is a broken bottom plan view thereof; Fig. 3 is a detail transverse vertical section of a modified form of brush; Fig. 4 is a broken bottom plan view of said modified form.

Referring to the drawing, 1 indicates a rectangular casing, open at the bottom, closed at the top and sides, and having removable ends 2. Upon the top of said casing, close to its four corners, are secured, by screws 3, rubber disks 4, the peripheries of which extend beyond the periphery of the casing, so that said disks serve as guards to protect furniture or the walls of the room against impact and abrasion by the sweeper casing when in use. Leading in a transverse direction and obliquely upward from the center of the top of the casing is a tubular conduit 5, formed at its upper end with a socket 6 adapted, in the manner common in the art, to receive the lower end of a pipe, not shown, which also serves as a handle, and which is adapted to be connected at its upper end with a hose leading to a suction apparatus to maintain a constant upward suction into said conduit from the interior of the casing. Within the casing, close to the sides thereof, are arranged two rollers, 7 having rubber surfaces 8, said rollers being pivoted in the ends of the casing, and the ends of said rollers rotating in very close proximity to the inner surface of the end pieces 2. The lower edges 9 of the sides of the casing slope downwardly inward, and to said sloping edges strips 10 of felt are secured by means of metal strips 11, which extend over said felt strips 10 and are secured to the said sloping lower edges by screws 12. Felt strips extend inward within the sides of the casing, and their free edges bear against the rubber surfaces of the rollers, and thereby prevent the free passage of air into the interior of the casing around the outer sides of said rollers, so that the only air which can enter the casing is that passing thereinto between the rollers. The rollers extend only slightly below the lower edges of the ends 2 of the casing, so that, when said rollers are on the surface to be swept, said lower edges are in close proximity to said surface, and therefore narrow streams of air enter the casing between the surface which is being swept and the lower edges of said ends.

14 indicates the back of a brush, having bristles 15, and attached by screws 16 to arms 17 depending from a metal top 18. Said arms can move in vertical guideways or recesses 19 in the ends of the casing, thereby confining the brush against movement in a direction transversely of its length. To said top 18 near its ends are secured guide posts 20, upon the upper threaded ends of which are screwed stop nuts 21, said upper ends being adapted to slide through apertures 22 formed in the tops of caps 23 screwed into cylindrical flanges 24, formed on the top of the casing. Within said caps are contained springs 25, the lower ends of which bear upon the metal top 18, while their upper ends bear against the under surfaces of the tops of the caps. Individual closed housings 26 surround the caps, and are secured by set screws 27 to the flanges 24. By means of these springs 25 the brush is pressed upon the surface to be cleaned. This pressure can be increased by screwing the caps into the flanges, while, by screwing them outward, the pressure is diminished. With this construction, as the sweeper is moved over the surface to be cleaned, the pressure of the springs causes the brushes to remove the dust from said surface, and the constant suction maintained by the suction apparatus draws the air and with it the dust from the ends of the casing to the center and up through the conduit.

Figs. 3 and 4 illustrate a modified form of brush, in which the agitating material consists of obliquely arranged vertical rectangular pieces 28 of felt, said pieces being confined at the top between flanges 29, being also retained in place by a square bolt 30 passing centrally through said pieces.

I claim:

1. In a pneumatic sweeper, the combination of a casing open at the bottom, a brush

- supported centrally in said casing, rollers parallel with said brush and on opposite sides thereof, the ends of said rollers moving in close proximity to the ends of the casing 5 and flexible strips supported by the casing, and contacting with the outer sides of said rollers, to exclude the passage of air over the outer sides of said rollers, substantially as described.
- 10 2. In a pneumatic sweeper, the combination of a casing open at the bottom, a brush supported centrally in said casing, rollers parallel with said brush and on opposite sides thereof, the ends of said rollers moving 15 in close proximity to the ends of the casing, means for varying the pressure of said brush upon the floor, a substantially air tight housing for said means, and flexible strips supported by the casing, and contacting with 20 the outer sides of said rollers, to exclude the

passage of air over the outer sides of said rollers, substantially as described.

3. In a pneumatic sweeper, the combination of a casing open at the bottom, a brush supported centrally in said casing, rollers 25 parallel with said brush and on opposite sides thereof, the ends of said rollers moving in close proximity to the ends of the casing, means located at each end of the brush for varying the pressure of said brush upon the 30 floor, and a substantially air tight housing for each of said means, substantially as described.

In testimony whereof I have hereunto set my hand in the presence of two subscribing 35 witnesses.

ALBERT E. MOORHEAD.
